LOCOMOTIVE EXHAUST NOZZLE

John W. Hulson, Chicago, Ill., assignor to Hulson Company, Keokuk, Iowa, a corporation of Iowa

Application June 1, 1944, Serial No. 538,288

5 Claims. (Cl. 230—96)

A well known type of locomotive exhaust nozzle comprises briefly, a hollow cylindrical body having a radially corrugated upper end providing it with circumferentially spaced radial ridges and with radial valleys between said ridges. Ports for upwardly discharging the exhaust steam, open through the ridges, and blower ports open through the bottoms of the valleys. The nozzle is manufactured with exhaust steam discharge ports of the maximum size ever needed, and a central plate of one size or another is secured upon the aforesaid body to overlap more or less of these ports to reduce their effective size, in a locomotive requiring that they be of less than said maximum size for best results.

While generally desirable and efficient, the above described nozzle is open to improvement in certain respects, as will now be explained.

When testing for steam leaks in pipes, super-heaters, nozzle stands, etc., the exhaust steam ports of the nozzle are temporarily sealed to prevent steam emission, and water is then admitted under pressure, with the result that any leaks will permit discharge of water and may be located. Such testing, however, does not locate any leaks in the means for conducting the steam, for "stand-by draught," to the blower ports, nor does it test the cast nozzle body for sand holes and the like which would permit blower steam to escape, and leaks of this nature should also be located and repaired to insure proper nozzle operation.

The central plate above mentioned (for exhaust steam port reduction) is a circular disk and it not only overlaps the inner ends of the exhaust steam ports but also overlaps the inner ends of the aforesaid valleys, interfering with smooth travel of the products of combustion in these valleys for entrainment with the blasts of steam emitted from the nozzle. Even when the locomotive is equipped with a modern tuyère-type grate which materially reduces the entrainment of cinders with the escaping products of combustion, some cinders still pass the screen and/or other arresting means and reach the exhaust nozzle, where such turbulence occurs that they inflict serious abrasion or "cinder cutting," often cutting through portions of the aforesaid radial ridges and enlarging the exhaust steam discharge ports, seriously affecting the locomotive draught.

The present invention aims to so improve the exhaust nozzle construction as to permit easy testing of the steam conducting means leading to the blower ports, and testing of the nozzle casting for leaks from these ports, as well as testing of passages, etc., leading to the exhaust steam

discharge ports; and to provide a construction in which the products of combustion and cinders suspended therein may become more smoothly entrained with the steam blasts from the nozzle to materially diminish cinder cutting of said nozzle.

With the foregoing in view, the invention resides in the novel subject matter hereinafter described and claimed, description being accomplished by reference to the accompanying drawings.

Figure 1 is a top plan view of the improved nozzle, part of the central member being broken away to show the full radial length of the exhaust steam discharge ports.

Fig. 2 is a side elevation.

Fig. 3 is a vertical sectional view on line 3—3 of Fig. 1.

Fig. 4 is a vertical sectional view on the plane of line 4—4 of Fig. 1 but showing all of the ports closed by means of a gasket and plate, for test purposes.

In the drawings above briefly described, a preferred construction has been illustrated and while that construction will be rather specifically described, variations may be made within the scope of the invention as claimed.

The hollow cylindrical body 5 is provided at its lower end with lugs 6 for bolting to the usual nozzle stand or table plate, and the upper end of said body is radially corrugated, providing it with circumferentially spaced radial ridges 7 and with radial valleys 8 between said ridges. The central portion 9 of the upper end of the body 5, and the top faces 10 of the ridges 7 are all flat and are disposed in a single horizontal plane. The valleys 8 are of V-form, are relatively deep at their outer ends, and gradually decrease to insignificant depth at their inner ends. The exhaust steam discharge ports 11 open through the flat top faces 10 of the ridges 7 and this is also true of the blower ports 12, said ports 12 being disposed at the outer ends of said ports 11 and leading upwardly from a circular steam duct 13 in the side wall 14 of the body 5. At 15, two internally tapped bosses are shown, either of which is plugged at 16 and the other of which is for connection with the usual blower pipe.

Secured upon the flat central portion 9 of the upper end of the body 5, is a conical deflector 17, the base of which overlaps the inner ends of the ports 11 to reduce the effective size of said ports. This conical deflector 17 is formed with vertical upwardly open peripheral grooves 18, the lower ends of which are in direct communication

with the shallow inner ends of the valleys 8. In the present showing, the deflector 17 is formed from a major upper section 19 and a minor lower section 20. If less port reduction be required, section 20 may be omitted and section 19 secured directly upon the body 5, or if more port reduction be necessary, a larger section may be substituted for said section 20. In each instance, there will be a peripherally grooved conical deflector upon the body with its grooves communicating with the valleys 8 to smoothly guide products of combustion and any cinders therein to the blasts of steam discharged through the ports 11. Moreover, the conical deflector 17 prevents the creation of violent eddy currents in the inner portions of the steam blasts flowing upwardly around the edge of the base of said deflector, whereas such eddy currents have been present when simply using a flat plate for port reduction, and have contributed to such turbulence of the products of combustion and cinders therein as to cause serious cinder cutting of the nozzle.

The deflector 17 is secured to the body 5 by a central cap screw 21, the head of which is located in a socket 22 in the upper end of said member, for protection. When this screw is removed, the section 20 may be removed, and a larger section can be substituted if necessary, or both sections 19 and 20 may be removed whenever a test for leakage is to be made. For testing, a flat gasket 23 and flat plate 24 may be clamped by a screw 25 upon the flat horizontal upper end of the body 5 as seen in Fig. 4, simultaneously closing all of the ports 11 and 12. Then steam under pressure may be used to test the entire nozzle and all water conducting means leading thereto.

From the foregoing and the accompanying drawings, it will be seen that novel provision has been made for attaining the desired ends, and attention is again invited to the possibility of making variations within the scope of the invention as claimed.

I claim:

1. A locomotive exhaust nozzle comprising a hollow cylindrical body having a radially corrugated upper end providing it with circumferentially spaced radial ridges and with radial valleys between said ridges, the upper faces of said ridges being all flat and disposed in a single horizontal plane, said upper end of said body having a solid central portion and radially arranged steam discharge ports opening through said flat upper faces of said ridges; the peripheral wall of said body having a circumferential steam duct, an inlet for said duct and blower ports leading upwardly from said duct and opening through said flat upper faces of said ridges; all portions of said upper end of said body being at least as low as said flat upper faces of said ridges for the purpose set forth.

upwardly from said duct and opening through said flat upper faces of said ridges, all portions of said upper end of said body being at least as low as said flat upper faces of said ridges and a cone-shaped deflecting member secured on said solid central portion of the upper end of the body.

2. A locomotive exhaust nozzle comprising a hollow cylindrical body having a radially corrugated upper end providing it with circumferentially spaced radial ridges and with radial valleys between said ridges, said valleys being relatively deep at their outer ends and being inclined to insignificant depth at their inner ends, said body having steam discharge ports opening through said ridges, and a central member secured upon said body and overlapping the inner ends of said ports, said central member having peripheral grooves communicating with the shallow inner ends of said radial valleys.

3. A locomotive exhaust nozzle comprising a hollow cylindrical body having a radially corrugated upper end providing it with circumferentially spaced radial ridges and with radial valleys between said ridges, said valleys being relatively deep at their outer ends and being inclined to insignificant depth at their inner ends, said body having steam discharge ports opening through said ridges, and a conical deflector secured upon the central portion of said upper end of said body, the base of said conical deflector overlapping the inner ends of said ports to reduce the effective size thereof, said conical deflector having vertical peripheral grooves the lower ends of which are in direct communication with the shallow inner ends of said radial valleys.

4. A structure as specified in claim 3; said conical deflector being composed of an upper major section and a lower minor section, the latter of which may be removed when less reduction of said ports is desired.

5. A locomotive exhaust nozzle comprising a hollow cylindrical body having a radially corrugated upper end providing it with circumferentially spaced radial ridges and with radial valleys between said ridges; the upper faces of said ridges being all flat and disposed in a single horizontal plane, said upper end of said body having steam discharge ports opening through said flat upper faces of said ridges; the peripheral wall of said body having a circumferential steam duct, an inlet for said duct and blower ports leading upwardly from said duct and opening through said flat upper faces of said ridges; all portions of said upper end of said body being at least as low as said flat upper faces of said ridges for the purpose set forth.

JOHN W. HULSON.
